attorney.

UNITED STATES PATENT OFFICE.

THOMAS S. MOFFETT, OF WALLA WALLA, WASHINGTON.

COMBINED NECK-YOKE AND COUPLING MEANS.

1,357,889.

Specification of Letters Patent.

Patented Nov. 2, 1920.

Application filed July 19, 1919. Serial No. 312,062.

To all whom it may concern:

Be it known that I, THOMAS S. MOFFETT, a citizen of the United States, residing at Walla Walla, in the county of Walla Walla 5 and State of Washington, have invented certain new and useful Improvements in Combined Neck-Yokes and Coupling Means, of which the following is a specification.

This invention relates to neckyoke and 10 coupling means and has for its objects to provide a means for supporting the tongue of a vehicle by means of a swivel joint, whereby the neckyoke is kept truly in line directly ahead of the tongue, and with the 15 center piece of the neckyoke made in one piece, and provided with mortised recesses to receive the arms of the neckyoke, and extension pieces to assist in holding said arms rigidly in place.

20 A further object is to provide a coupling means whose male portion is simple to construct and by aid of its extension pieces is simple to install on the tongue and which will remain permanent.

25 A further object is to provide a means on which the reins cannot catch and which is easy to remove from the tongue, easy to replace and proof against accidental dislodgment.

30 A further object is to provide a neckyoke having swiveled harness rings in the ends thereof that will receive the breast strap without trouble and that will revolve and give ample play and not twist the straps.

35 A further object is to provide a means to inclose the end of the tongue so that the harness reins cannot catch thereon.

With these and other objects in view reference is had to the accompanying drawing, 40 in which—

Figure 1 is a plan view of my invention;

Fig. 2 is a sectional view of the center piece;

Fig. 3 is a rear elevation of the center 45 piece;

Fig. 4 is a vertical sectional view of the cap and revolute member, enlarged;

Fig. 5 is a side elevation of the revolute member and ring enlarged;

50 Fig. 6 is a plan view of the socket; and

Fig. 7 is an end elevation of the ring, enlarged.

In the drawings similar numerals refer to similar parts throughout and 1 is a one 55 piece center piece having a recess 2 in each end thereof to receive the arms 3 of the

neckyoke. This center piece has a ball socket 4 situated in the center thereof and an oblong channel 5 communicating therewith with its major diameter extending in 60 the direction of the longitudinal axis of the neckyoke and of a width slightly in excess of the diameter of the ball socket, and a minor diameter of less than the diameter of the ball socket.

65 On the ends of the center piece are extension pieces 6 which are cast or made integral with the center piece and which are designed to aid in holding the arms 3 in rigid connection with the center piece.

70 The arms 3 are mortised into the center piece and are held securely by means of the rivets 7. On the outer ends of the arms are caps 8 which, as shown in the large view, Fig. 4, are hollow, having an orifice 9 provided in the ends thereof to receive the revolute member 10 to which the ring 11 is hingedly mounted. The orifice 9 being smaller than the end of the cap forms a shoulder 12 against which the revolute 75 member is held, and to prevent this member from accidental dislodgment the end 13 of the arms is placed so that it forms a backing for it.

75 The sleeve shown in Fig. 6 consists of a 80 socket piece 14 which is extended to form a neck 15 upon which is a ball 16 having two flat sides 17. The diameter of the ball equals the diameter of the ball socket 4, and the distance between the two flat sides is less 85 than that of the ball socket and equals the diameter of the minor axis of the channel 5. The neck 15 is made of smaller diameter than the above mentioned distance between the two flat sides to leave a shoulder 18. On 90 the rear end of the sleeve and integral therewith are extension pieces 19 similar to those of the extension pieces 6 on the center piece 1 and are intended to aid in holding the tongue and sleeve rigidly together by means 95 of the rivets 20 and the bolt 21, see Fig. 1, the tongue being mortised to fit into the sleeve as shown by the dotted lines in Fig. 1.

100 In use the neckyoke is placed against the ball 16 with the longitudinal axis of the neckyoke in a vertical position, the channel 5 is then in register with the flattened sides of the ball which is now free to enter the ball socket; a quarter turn makes the coupling secure, and in hitching the horses to 105 the neckyoke the breast strap is passed through the rings 11 which are readily re-

volved (should they be not in position) to receive the strap. The reins may now remain loose as there can be no danger of catching over the end of the tongue, as it is 5 completely covered.

The bolt 21 may be a ringed bolt if desired.

The right of slight changes and modifications is reserved coming within the scope of 10 my invention.

Having thus described my invention I claim—

In the combination of a neckyoke and coupling means, a one piece center piece centrally disposed between a pair of arms and 15 of a form to afford a continuous unbroken surface to the neckyoke, a ball socket centrally positioned in said center piece, said ball socket being designed to receive a ball suitably attached to a tongue, and arms mortised into and flush with said center piece. 20

In testimony whereof I affix my signature.

THOMAS S. MOFFETT.
